INSERTION OF FASTENINGS

George Goddu, Winchester, Mass., assignor to
United Shoe Machinery Corporation, Paterson,
N. J., a corporation of Massachusetts

Application May 3, 1930, Serial No. 449,457

12 Claims. (Cl. 1—20)

This invention relates to the insertion of fastenings, particularly in the manufacture of shoes, and is illustrated herein with reference to the securing of a shoe upper in lasted relation to an

5 insole and last by fastenings inserted through the shoe upper into the insole and clenched substantially in the form of a helix.

Goodyear welt shoes, as well as shoes of some other kinds, are made with an insole having a 10 rib to which the shoe upper is secured during or after the lasting operation by staples driven through the shoe upper into the rib of the insole and clenched by an anvil bearing against the inner surface of the rib. In many instances the

15 staples are inserted by a side lasting machine which is utilized to work the portion of the shoe upper extending between the heel breast line and the tip line into lasted relation to the last and insole. They are, therefore, the sole means relied

20 upon to hold the upper in lasted position up to the time of the inseaming operation by which the welt is secured to the lasted upper and insole. It is therefore important that the upper be stapled to the rib in a manner which will in-

25 sure that the rib cannot yield outwardly, thereby lessening the tension of the lasted upper and resulting in a poorly lasted shoe.

It is accordingly an object of the present invention to provide for the insertion and clenching 30 of such staples in a manner which not only will securely anchor the staples in the insole but will also prevent the rib from yielding outwardly under the tension imposed by the lasted upper leather. As illustrated herein this is performed

35 by clenching the entering ends of the legs of the staples in a substantially helical form against an anvil positioned in the angle between the inner surface of the rib and the outer surface of the insole and closely adjacent to the base of the rib, 40 the anvil being provided with clenching cavities formed and arranged to clench the entering ends of the legs of the staple in a substantially helical form, the helically clenched portions lying in the extreme base of the rib of the insole and in the

45 substance of the insole adjacent to but below the rib. The strain exerted by the shoe upper on the staples is thus transmitted to the body of the insole in such a way that there is no danger of the rib yielding and allowing the shoe upper to 50 become slack.

It should be understood that the invention is not limited to use in connection with the staple lasting of shoes. Fastenings clenched in accordance with the invention may be used for 55 other purposes than the securing of shoe uppers

in lasted relation and fastenings other than staples may be clenched in accordance with the invention.

In various of its aspects my invention comprises 60 a staple or other fastening anchored with a substantially helical clench in the stock in which it is driven; a shoe or other article parts of which are secured together by a fastening or fastenings clenched in a substantially helical form; and an improvement in methods of inserting staples or 65 other fastenings characterized by the progressive clenching of the entering ends of the fastenings in a three-dimensional curve such as a helix.

With the above and other objects and features in view the invention will now be described 70 in connection with the accompanying drawing and pointed out in the claims.

In the drawing,

Fig. 1 is a side elevation of a fragment of a 75 side lasting machine provided with means for inserting staples to secure a shoe upper in lasted relation to an insole and last, the shoe upper, the insole and the last being shown in cross section;

Fig. 2 is a view on a somewhat larger scale of 80 the work engaging portions of the machine of Fig. 1 and of the work piece which they engage, showing particularly the form and the location in which the staple is clenched;

Fig. 3 is a diagrammatic perspective view on 85 a still larger scale showing the driver and clenching anvil of the machine together with a staple substantially at the conclusion of the clenching operation;

Fig. 4 is a view on yet a larger scale of the 90 clenching anvil of the machine, a partly clenched staple being indicated at the left-hand side of that figure;

Figs. 5 and 6 are longitudinal sectional views 95 through the clenching anvil on the line V—V of Fig. 4, showing the relation of the anvil to a staple at different points in the clenching operation;

Fig. 7 is a section on the line VII—VII of Figs. 4 and 6; and

Fig. 8 is a section on the line VIII—VIII of 100 Figs. 4 and 6.

As pointed out above the invention is disclosed herein with reference to the securing of a shoe upper in lasted relation to an insole and last by 105 staples inserted through the shoe upper into the insole and clenched substantially in the form of a helix. Thus Figs. 1 and 2 show the nozzle 10, driver 12 and anvil 14 of a staple side lasting machine which may be of the character fully dis- 110

closed in Letters Patent of the United States No. 1,796,451, granted March 17, 1931, on a copending application filed in my name, to which reference may be had for a complete disclosure of the machine. It will be understood that during the performance of the lasting operation the shoe upper 18 is worked progressively into lasted relation to the last 20 and insole 22, being secured in that relation by staples 24 inserted through the marginal portion 16 of the upper 18 into the rib 26 of the insole 22, the entering ends of the legs of the staples 24 emerging from the inner surface of the rib 26 and being turned back into the substance of the rib and clenched by clenching cavities 28 formed in the anvil 14. Conveniently the anvil 14 is adjustably mounted as indicated at 30 in Fig. 1.

In accordance with the present invention the legs of the staples are clenched by the clenching cavities 28 of the anvil 14 in a substantially helical form, as indicated in Figs. 2, 3, 4 and 6, the clenched portion of the staple, moreover, being located in the rib 26 at its extreme base and in the body of the insole adjacent to the rib, as best shown in Fig. 2. To accomplish this the portion of the anvil 14 containing the clenching cavities 28 is positioned against the base of the rib as illustrated in Figs. 1 and 2. The formation of the clenching surface of the cavities 28 is a three-dimensional curve, that is to say it is a curved surface every cross section of which is a curved line, and it is located non-symmetrically with respect to the line of drive as will be evident by a comparison of Figs. 4, 6, 7 and 8. Referring particularly to Fig. 4, it will be noted that the line of drive (represented by a fragment of the cross bar of the staple indicated at 31 and the cross section of a leg of the staple indicated at 32) is considerably above the line V—V with respect to which portions of the clenching cavities adjacent to the line V—V are symmetrical. By reference to Figs. 5 and 6, and to Figs. 7 and 8, which are cross sections on the lines VII—VII and VIII—VIII respectively of Figs. 4 and 6, it will be seen that the clenching cavities are of such a formation that when struck by the entering ends of the legs of a staple they tend to deflect the entering ends of the legs of the staple progressively away from each other, symmetrically with respect to the median plane of the staple and at the same time downwardly (as viewed in Fig. 4) and ultimately back in the general direction from which they have come, as indicated in Figs. 5 and 6, the result being a substantially helical or corkscrew clench as shown in Figs. 2 and 3 and as indicated by comparison of Figs. 4 and 6.

In order to facilitate the positioning of the anvil 14 at the base of the rib 16, the lower portion of the anvil is cut off as indicated by the line 40 in Fig. 4. The portions of the clenching surfaces of the cavities 28 which are thus removed are non-essential and the clenching operation is in no way interfered with by the elimination of this portion of the anvil.

When staples inserted to hold the upper in lasted relation to the insole and last of a Good-year welt shoe are clenched in this fashion the entering ends of the staple legs are engaged when they emerge from the inner surface of the rib 16 of the insole 22 by the clenching cavities 28 of the anvil 14 and are curved progressively through a substantially helical path back into the rib 16 of the insole 22 and toward the inner surface of the insole, finally anchoring themselves in the insole in a manner which prevents the rib from

yielding under the tension of the lasted shoe upper.

The staple inserting mechanism described above is not claimed herein since it is claimed in my copending divisional application Serial No. 584,396, filed Jan. 2, 1932. 80

Having thus described my invention what I claim as new and desire to secure by Letters Patent of the United States is:

1. A staple formed of small wire the legs of which are anchored with a substantially helical clench in stock into which the staple is driven. 85

2. A staple formed of small wire the legs of which pass completely through stock into which the staple is driven and in which said legs are anchored with a substantially helical clench. 90

3. An article comprising two or more layers of material secured together by one or more staples the ends of the legs of which are in a plane substantially normal to the longitudinal axis of the legs and inserted through two or more of the layers of material and are clenched in the material in a substantially helical form. 95

4. An article comprising a plurality of layers of material secured together by a staple the legs of which pass through the layers of material and are clenched in the material in a substantially helical form, the planes of the ends of the legs of the staple being substantially normal to the longitudinal axis of the legs. 100

5. A shoe having its upper secured in lasted relation to its insole by a fastening inserted through the upper into the insole and clenched in a substantially helical form. 105

6. A shoe having its upper secured in lasted relation to a ribbed insole by staples the legs of which are inserted through the upper into the rib of the insole and are clenched in the rib of the insole in a substantially helical form. 110

7. A shoe having its upper secured in lasted relation to a rib of its insole by fastenings which pass through the upper and the rib of the insole and are clenched in the substance of the insole substantially in the form of a helix located at the base of the rib of the insole and extending from the non-clenched portion of each fastening toward the inner surface of the insole without passing through said surface. 115

8. A shoe having its upper secured in lasted relation to its insole by staples the legs of which pass through the upper and into the insole and are clenched in the substance of the insole substantially in the form of a helix extending from the non-clenched portions of the staple legs toward the inner surface of the insole but without passing through said surface. 120

9. A shoe having its upper secured in lasted relation to a ribbed insole by staples the legs of which pass through the upper and the rib of the insole and are clenched in the substance of the insole substantially in the form of a helix extending from the non-clenched portions of the staple legs toward the inner surface of the insole. 125

10. That improvement in methods of inserting staples through a shoe upper into an insole to hold the upper in lasted relation to the insole characterized by deflecting the legs of the staples simultaneously and progressively toward the inner surface of the insole and lengthwise of the shoe and widthwise of the shoe as they are clenched, whereby the end portions of the legs of the staple are clenched each in a three-dimensional curve. 130

11. That improvement in methods of manufacturing shoes which comprises inserting fas- 135

tenings through a shoe upper into the rib of an insole to hold the upper in lasted relation to the rib of the insole characterized by deflecting the entering end of each fastening as it comes 5 through the rib progressively back into the rib of the insole and lengthwise of the shoe and widthwise of the shoe, thereby clenching the end of the fastening in a substantially helical form. to hold the upper in lasted relation to the insole characterized by deflecting the legs of the staples as they come through the rib simultaneously and progressively toward the inner surface of the insole and lengthwise of the shoe and widthwise of the shoe, whereby the end portions of the legs of the staple move each in a three-dimensional path as they are clenched. 80

12. That improvement in methods of inserting 10 staples through a shoe upper into a ribbed insole
